UNITED STATES PATENT OFFICE.

BENJAMINE LEVINE, OF BROOKLYN, NEW YORK.

BOX-BED-SPRING CONSTRUCTION.

1,382,432.

Specification of Letters Patent. Patented June 21, 1921.

Application filed November 11, 1920. Serial No. 423,411.

To all whom it may concern:

Be it known that I, BENJAMINE LEVINE, a citizen of the United States, and a resident of the city of New York, borough of Brooklyn, in the county of Kings and State of New York, have invented a new and Improved Box-Bed-Spring Construction, of which the following is a full, clear, and exact description.

10 This invention relates to box bed-spring constructions and has for an object to provide a simple, compact box spring frame which is insectproof.

Another object of the invention resides in 15 the provision of a frame having a cover of fabric, or other suitable material, the ends of which are turned over the edges of the bottom of the frame and clamped between the edges and a closure portion.

20 A further object resides in the particular construction and arrangement of parts hereinafter described and claimed and shown in the accompanying drawings.

Hitherto box bed-spring frame structures 25 have been open to the objection that they were not dirt and insect-proof. I overcome this objection by providing my box spring frame with a cover of fabric, or other suitable material, the end portions of which are 30 turned over the bottom edges of the frame and fastened thereto, and the bottom is then closed by providing a tight-fitting closure portion which clamps against the edges of the fabric. Another feature resides in the 35 provision of a metallic seal around the abutting edges of the closure and the edges of the frame to further effectively prevent insects and dirt from getting into the interior of the frame.

40 The invention is shown in the drawings, of which—

Figure 1 is a partial perspective view of the frame having one portion cut away to show the interior construction; and

45 Fig. 2 is a modified form of my construction.

As shown in the drawings, the invention 50 comprises the usual rectangular frame 1, preferably of wood, which is open at the bottom and the top. Along the top, open portion of the frame a layer of upholstery 2 is placed, beneath which are disposed the usual springs 3. The edges of the frame along the bottom opening are tapered, as 55 shown at 4, which taper faces upwardly, as shown in Fig. 1. A cover of any suitable

material, such as leather or fabric, is placed over the top of the frame, covering the upholstery, and drawn down along the sides; and the free edges of this cover or fabric 60 are drawn over the bottom edges and fastened to the inside edges of the frame 1, as shown at 6.

The bottom opening of the frame is adapted to be closed by a closure portion 7, which 65 is likewise covered with fabric or other suitable material 8, the free ends of which are drawn over the edges of the closure portion 7, as shown at 9, and fastened thereto in any suitable manner. The inner edges 70 of the closure portion 7 are provided with a tapered face, as shown at 10, which is adapted to lie along and abut the tapered portion 4 above mentioned. This closure portion 7 is adapted to tightly fit into the 75 opening in the bottom of the frame 1 and may be fastened thereto by any suitable means, such as nails or screws, or may be glued thereto. It will thus be seen that when the closure portion is in place, and 80 assuming the fabric portion 5 to be sewed, as shown at 11, along the necessary seams there is no opening in the structure through which dirt or insects could reach the interior of the frame. The abutting edges, such as 85 12, between the closure portion and the bottom edges of the frame are very tightly sealed.

In the modification shown in Fig. 2, a plate 13 of any suitable metal or other material is fastened in any suitable manner to the bottom portion of the frame and covers the bottom over the abutting edges 12 above mentioned.

It is apparent that the action of the closure portion in clamping the ends of the cover between itself and the body of the frame 1 not only makes a very tight joint but also tends to tighten the cover and hold it firmly in place. Other forms than the 100 beveled as shown may be used so long as a tight-fitting closure portion is provided which clamps the cover fabric between itself and the frame.

What I claim is:

1. A box bed-spring construction comprising a frame having an open bottom, a cover for the frame having its ends extending over the edges of the bottom and fastened to the frame, and a closure adapted to 110 fit tightly into the open bottom and clamp the fabric between it and the frame.

2. A box bed-spring construction comprising a frame having an open bottom, outwardly facing tapered surfaces along the edges of the bottom, a closure portion provided with corresponding tapered surfaces adapted to fit into and bear against the tapered surfaces of the bottom, and a cover portion having its ends extending over the edges of the bottom and adapted to be gripped between the frame and the closure portion.

3. A box bed-spring construction comprising a frame having an open bottom, an outwardly extending tapered surface along the edges of the bottom, upholstery filling the top of said frame, springs beneath the upholstery, a cover adapted to fit over the upholstery and the frame having

its free end portions extending over the edges of the bottom, and a closure provided with an inwardly facing tapered surface adapted to bear against the fabric and clamp it between the closure and the frame.

4. A box bed-spring construction comprising a frame having an open bottom, a tight-fitting closure portion adapted to fit into the open bottom, a cover portion adapted to extend over the frame with its free edges extending over the edges of the bottom portion and adapted to be gripped between the closure portion and the frame, and a metal cover suitably fastened to the bottom portion and extending over the above abutting edges of the closure and the frame.

BENJAMINE LEVINE.
